his attorney

SIMEON BROWN, OF UTICA, OHIO.

Letters Patent No. 89,284, dated April 27, 1869.

IMPROVED ADJUSTABLE GATE FOR GRAIN-ELEVATORS.

The Schedule referred to in these Letters Patent and making part of the same.

To all whom it may concern:

Be it known that I, SIMEON BROWN, of Utica, in the county of Licking, and State of Ohio, have invented a new and useful Improvement in Grain-Elevators; and I do hereby declare that the following is a full, clear, and exact description thereof, reference being had to the accompanying drawing, and to the letters of reference marked thereon.

The nature of my invention consists in attaching an adjustable feed-gate to grain-elevators, in such a manner as to effectually prevent choking, and at the same time to regulate the quantity of grain fed to the elevator.

To enable others skilled in the art to which my invention appertains to make and use my invention, I will proceed to describe its construction and operation.

In the drawing—

A represents the outside frame, or casing, of an elevator, with the top removed, so as to show the upper drum D, endless band B, and buckets b, which form the elevating device.

C is a lever, pivoted at one end, to a bracket, c, and working easily in a forked guide, c', which prevents lateral motion of the lever.

S is a spiral spring, the tendency of which is to draw the lever C downward.

The free end of the lever C is connected by a rod, R, to another lever, E, one end of which is pivoted at e, to the casing A, and at the other end is attached the regulating feed-gate G, which slides in a groove formed in the partition between the casing A and the

hopper H, at the bottom of which is an aperture, F, through which the grain passes to the inside of the casing, where it is elevated by the buckets b, which aperture F is closed, or partially closed, by the gate G, when not in motion.

The operation is as follows:

As the drum D revolves, carrying the endless band B and buckets b, a crank-pin, p, on the drum-shaft d, raises the free end of the lever C, which motion, by means of rod R and lever E, raises the gate G, and keeps it up until the pin p has passed the end of the lever C, when the action of the spring S upon the lever C, rod R, and lever E, will lower the gate G, and close, or partially close the aperture F.

The quantity of grain passing through the aperture F may be regulated by adjusting the rod R to the different holes in the lever E.

The reciprocating motion of the gate G, and the consequent alternate opening and closing of the aperture F, effectually prevent all choking and clogging of the material passing to the elevator.

Having thus described my invention,

What I claim, and desire to secure by Letters Patent, is—

The lever C, spring S, and crank-pin p, or its equivalent, in combination with the rod R, lever E, gate G, hopper H, and elevator B, substantially as shown and described.

SIMEON BROWN.
